PORTABLE DEVICE FOR CONTINUOUS
PRESSURE POLITZERIZATIONOrr E. Reynolds, Washington, D. C., and
Loyal G. Goff, Midway Island, Va.

Application December 27, 1945, Serial No. 637,408

12 Claims. (Cl. 128—1)

1

This invention relates to politzerization and more particularly to a method and apparatus for continuous pressure politzerization.

The phenomenon of ear pain occurring as a result of alterations in external barometric pressure has been known and recognized since the beginnings of aviation. However, the phenomenon was not fully described until 1937, when Armstrong and Heim published their work "The Effect of Flight on the Middle Ear," on the anatomical and physiological causes of the disorder which they named "aero-otitis media" (an inflammation of the middle ear cavity caused by gas forces). A description of the anatomical and physiological etiology of this disease may be found in the above reference.

This phenomenon is extremely common in aviation in the case of aviators both when suffering from colds and when forced to descend at high rates of speed, and to air passengers who may have structural abnormalities. These abnormalities include dental malocclusion, or scar tissue in the region of the ostium or over-growth of lymphoid tissue. Likewise, the persons may be suffering from upper respiratory tract infections, such as head colds, or they may simply be untrained in the methods of "clearing" the ears during barometric pressure changes. Prophylactic measures such as indoctrination in efficient techniques for opening the Eustachian tube, or by use of vasodilator substances such as ephedrine, neosynephrine, benzidrene, and the like, may be of great value in preventing these symptoms. However, once a "block" of sufficient degree is reached, only two means are available for relief. The first, and most obvious, is resuscitation until the pressure differential is reduced enough to permit equalization. This means, however, is impractical in the great majority of cases. The other means is politzerization.

The original Politzer method, developed by Adam Politzer, an Austrian otologist, before aviation was sufficiently developed to be a factor in ear maladies, consists of inflation of the Eustachian tube and middle ear by forcing air into the nasal cavity through a nose piece by manually collapsing a pear shaped rubber bag (similar to a squeeze bulb) at the instant the patient swallows. This original Politzer method allows application of a momentary burst of high pressure at a time when the muscles of the Eustachian tube are attempting to open it and in repeated attempts often produces relief. However, this original method is disadvantageous in that substantially perfect synchronization is re-

quired in the efforts of both the operator and the patient. Furthermore, there is no safety means such as a relief valve or pressure gauge, and consequently the operator must be experienced and perform the technique with caution in order to employ only safe pressures.

Modifications of this original method have been made by the use of an external source of compressed air or gas (from 30 to 1000 lbs. per 10 inch) derived either from a stationary air pump or pressure cylinder which necessitates the use of a reducing valve to control the pressure within safe limits. These newer methods have been identified as "continuous pressure" politzerization as distinct from the "instantaneous" politzerization of the original method. The continuous methods have the distinct advantage of freedom from the exact synchronization of application of pressure and swallowing, required with the instantaneous technique. These prior continuous pressure methods, while surmounting the problem in theory, have not been completely successful, however, and have been unsatisfactory on several counts. In the first place relatively expensive control equipment is necessary to prevent the application of excessive pressures which might cause permanent damage to the tissues of the middle ear and ear drum of the patient. Secondly, the use of gas, such as oxygen, is undesirable due to the fact that it is gradually absorbed through the tissues of the ear leaving the patient in the same condition as before politzerization. Furthermore, there are numerous physical disadvantages, such as expense of equipment, lack of portability which prevents it from being carried by a physician in his hand-bag, difficulty and expense of maintenance and the danger associated with the handling and controlling of high pressure gases. The recharging 20 of the cylinders would be a major problem in some localities. Furthermore, most gases under pressure must be handled carefully to prevent an explosion of the cylinder. The use of a cylinder necessitates the use of a reducing valve 25 which creates an additional expense and another possible source of mechanical failure. Should the reducing valve fail to function properly, and the full pressure from the cylinder be injected 30 into the patient's oral-nasal cavity, rupture of 35 the ear drum could easily result.

Having in mind the above and other defects of the prior art methods and apparatus, it is an object of this invention to provide a method of and an apparatus for practicing continuous 40 pressure politzerization that is completely effec-

tive and absolutely safe and which is simple and compact in arrangement, so that it is readily carried in a physician's hand-bag, and inexpensive in construction. Furthermore, the operation must be such that it may be performed by an inexperienced operator without danger of injury to the patient.

The foregoing objects and others ancillary thereto are preferably accomplished, in accordance with the basic concept of this invention, by providing a portable source of compressed atmospheric air at low pressure, such as a small hand pump, adapted to supply air to a pressure reservoir, which also acts as a surge tank, wherein the pressure is controlled and maintained under a given maximum by a suitable safety relief valve or mercury manometer constructed to indicate pressure as well as to relieve pressure in the surge tank. An orificial applicator (preferably, but not necessarily, a nasal applicator) is in communication with the surge tank and consequently is adapted to supply a continuous pressure of atmospheric air that is constantly maintained below a pressure that might be injurious to the patient. It will be seen that in actual practice the applicator or nose piece may be placed in a nostril, ipsilateral to the ear block, and the other nostril closed with the finger. In view of the fact that a constant or continuous pressure is being delivered through the nostril to the oral cavity, the patient may swallow to exercise the Eustachian tube at any time during the administration of the pressure and as said pressure is built-up from zero to the maximum safe pressure, whereupon different degrees of safe pressure of air is admitted to the middle ear cavity until the patient experiences immediate relief. Thus, with the present invention absolute safety to the patient is assured and it does not require synchronization between the swallow of the patient with the momentary blast or repeated blasts as in the original Politzer method.

The novel features that are considered characteristic of this invention are set forth with particularity in the appended claims. The invention itself, however, both as to its organization and its method of operation, together with additional objects and advantages thereof, will best be understood from the following description of specific embodiments, when read in connection with the accompanying drawings, wherein like reference characters indicate like parts throughout, and in which:

Figure 1 is a front view in elevation of the preferred embodiment of the present politzerizer;

Figure 2 is a front view in elevation of a modified structure particularly adapted for portability;

Figure 3 is a front view in elevation of a sphygmomanometer adapted to operate as a politzerizer;

Figure 4 is an exploded view, partially in cross-section, of the adaptor employed in the structure shown in Figure 3; and

Figure 5 is a fragmentary view in cross-section showing the safety valve employed in the structure shown in Figure 2.

According to one modification of the apparatus, which is particularly suitable for general use, reference being made to Fig. 1 of the drawings, the instrument may comprise a hand pump 1, in the form of an ordinary collapsible bulb, which is provided at or adjacent its intake end with a check valve 2 and at or adjacent its dis-

charge end a check valve 2a, these check valves being unidirectional, and the bulb is connected by a tube 3 to a T fitting 4 that is connected by a tube 5 to an orificial applicator 7. The T fitting may also be connected by a tube 8 to an inlet 9 of a pressure surge tank 10. The check valve 2 admits air into the hand bulb 1 when the latter is extending and closes when the latter is collapsed while the check valve 2a opens when the bulb is collapsed and closes when being inflated or extended. The surge tank 10 is in communication, through outlet 12 and tube 13, with manometer 14. The manometer 14 is shown in Fig. 1 as being of the mercury type which comprises a U-shaped tube containing a predetermined quantity of mercury. As a safety feature for use in the event of transporting the apparatus, and preventing mercury loss from the tube 14, the upper extremities of the mercury manometer are fitted with stop-cocks 15 which may be closed to trap the mercury within the tube. The outlet end of the manometer 14 is connected by a tube 16 to the inlet 17 of a trap 18 that is provided with a vent 19. A scale 20 is positioned adjacent the outlet reach of the manometer tube 14, the lower end of the scale 20 being positioned substantially level with the surface of the mercury when it is in position of rest. As a matter of convenience the apparatus may be attached, as by clips 21, to a supporting board 22 that is mounted in a generally upright position on a base 23.

A hand source of pressure, such as the hand bulb 1, is preferred to operate the instrument as it does not require the use of elaborate mechanical appliances and affords the greatest economy, efficiency and dependability.

Besides serving in the capacity of furnishing steady, even pressure, the pressure surge tank 10 is located between the orificial applicator 7 and the mercury manometer 14 and thereby serves in a safety capacity. Should the patient suddenly gasp and subject the manometer 14 to excessive reverse pressure, the mercury would be withdrawn from the manometer. By the present construction, however, the mercury will be retained in the surge tank 10 and not inhaled by the patient. The surge tank 10 is preferably of 500 cc. capacity, which is sufficient to deliver a constant flow of air in the necessary quantity for efficient performance of the instrument but, on the other hand, is small enough to preclude bulkiness. The capacity of the surge tank 10 may vary, depending upon the output of the hand pump or bulb 1 and may vary between 200 cc. to 1000 cc. Any surge tank, however, above 1000 cc. restricts the portability of the device and, therefore would limit one of the advantages of the present device.

The U-column mercury manometer 14 is calibrated in millimeters of mercury pressure and performs the dual functions of pressure determination and acting as a relief safety valve. The safety valve action is derived by the proper adjustment of the mercury column so that the mercury will be entirely displaced to the outlet arm of the manometer before a dangerously high maximum pressure is developed, thereby permitting the excess pressure to bubble through the mercury. Otherwise the excess pressure might be forced into the patient's oral-nasal cavity, causing discomfort, if not injury. The accuracy of the mercury type of gauge is such that it is used to check and calibrate all mechanical gauges. It also has advantages over a mechan-

ical gauge in that it contains nothing to break down or get out of adjustment, and is more economical.

The calibration of the manometer 14, by the scale 20, is in mm. Hg (millimeters of mercury), and, as a matter of convenience, is divided into three sections identified as "safe," "caution," and "extreme caution," which are colored respectively green, yellow and red. The "safe" or green area is 23 mm. high, the "caution" or yellow is 27 mm. and the "extreme caution" or red 50 mm. In determining the pressure used, the reading must be doubled as the difference in the mercury columns is twice the amount of rise in the side calibrated. The sum of the green and yellow areas is 50 mm. which equals an actual pressure of 100 mm. mercury. This is considered by many authorities to be the optimum pressure for politzerization.

In some few persistent cases, however, pressures up to and including 200 mm. Hg have been used with excellent results and no undesirable effects. For this reason, the instrument is adjusted to what is presently and generally considered safe pressure deliverance of 200 mm. of mercury, although this pressure may be that which is physiologically tolerable to the patient. In the majority of cases, however, 75 to 100 mm. of mercury is sufficient for satisfactory politzerization. The manometer 14 is adjusted so that pressure in excess of the predetermined maximum cannot be used through regulation of the height of the mercury column when it is at rest. The height of the mercury column is such that when the maximum pressure is reached all the mercury is transferred to the calibrated arm of the manometer allowing air to bubble through it, thus maintaining a pressure not greater than that which has been predetermined.

In the use of this instrument the subject or patient is given a mouth full of water and is instructed to take a deep breath and hold it. The nose piece 7 is placed in the nostril of the patient, ipsilateral to the ear block and the other nostril closed with the finger with his mouth closed, and the hand bulb 1 is actuated repeatedly until the desired pressure is read on the scale 20 of the instrument, at which time the subject is told to swallow and immediate relief follows. In mild cases, the patient will, or will be told to, swallow when the pressure is about 75 mm.; and, if relief is not experienced, the bulb will be further actuated to deliver a continuous pressure to the patient until about 100 mm. is registered, when swallowing process should be repeated, and so on, until relief is experienced or until the maximum safety limit of pressure has been reached. In swallowing, the throat muscles are contracted so that the openings to the middle ear cavity are stretched and allow the air, which is under constant or continuous and safe pressure, to enter freely.

A simplified and more compact structure, as shown in Fig. 2, may be provided in portable form, in order to accommodate more widespread application of the present improved method. In Fig. 2, a hand bulb 1, provided with check-valves 2 and 2a, is connected by a tube 30 to a surge tank which is in the form of a portable box 31 forming an airtight chamber. An aneroid manometer 32 or other suitable pressure gauge is positioned in one wall of the box 31, the dial 33 of the manometer being visible through a sealed aperture 34 in the box wall. The manometer 32 is in communication with the interior

of the box 31 so that the dial 33 is responsive to and indicates the pressure within the chamber. The tube 30 is connected within the box 31 to a tube 35 having the nasal nozzle or other type of orificial applicator 7 at the other end thereof. A safety or relief valve 36 is seated in one wall of the box 31 and is in communication with the chamber therein in order to preclude the development of pressures above the desired maximum.

The relief valve 36 is shown in detail in Fig. 5. It is of known type and may comprise a cylindrical body 37 that is inturned at its lower edges to provide shoulders 38 and aperture 39. Cross-bars 40 extend diametrically across the top of the body 37 to form a seat for a helical spring 41 which normally seats a valve 42 against the shoulders 38. The body 37 may be seated in a wall of the box 31 in any desired manner and is shown as having a threaded portion 43 adapted to cooperate with a threaded aperture 44 in the wall of the box 31. It will be understood that the tension of the spring 41 may be selected to resist pressures up to a predetermined maximum degree hereinbefore specified. When the pressure exceeds the desired limit the valve 42 is forced upwardly and compresses the spring 41, whereupon the air escapes through the aperture 39 past valve 42 through the body 37 and past the cross-bars 40.

The type of instrument shown in Fig. 2 is employed with the same technique as described in connection with Figure 1 and is desirable because of its compactness and its ready portability as surge box or tank 31 may be of dimensions to occupy 200 cubic inches net volume. In addition, it is sturdy and its elements are not subject to easy breakage and is not required to be retained in an upright position during operation, as is the case with the apparatus in Fig. 1. On the other hand, it necessitates both a manometer of the mechanical type and a separate safety valve to replace the mercury manometer. Nevertheless, this instrument affords an easy and practical application of the present improved method under all circumstances.

Still another practical application of the present method of continuous pressure politzerization may be effected by the adaption of the sphygmomanometer for this purpose. The sphygmomanometer, which is used for determining blood pressure, is one of the basic pieces of a physician's equipment. Accordingly, by adapting this instrument, continuous pressure politzerization may be universally practiced. As shown in Fig. 3, the sphygmomanometer comprises an air tight tubular bag (or cuff) 50 which is usually made of rubberized cloth. The bag 50 is normally provided with an extended tailpiece 52 or laterally extending tapes 53 for securing it around a patient's arm. A pressure gauge 54 is connected to the bag 50 by a tube 55, and a hand bulb 1 having valves 2, 2a is connected to the bag 50 by a tube 56.

In order to adapt this instrument for the practice of politzerization the tube 56 is cut and the severed ends connected to the cross-arms of a T section 4. The branch-arm of the T section 4 is connected by a tube 5 to a nozzle such as the nasal applicator 7 in a manner identical to that shown in Fig. 1. By this arrangement the bag 50 performs the function of a surge tank wherein pressure may be developed by the hand bulb 1 to the desired degree as indicated by the gauge 54. For most efficient use, it is preferred that the

bag 50 is rolled loosely and secured in this position by the tapes 53, or other appropriate fasteners attached to tail-piece 52, so as to restrict the volume capacity of the reservoir or surge tank formed by bag 50 to about 500 cc. or the capacity of about a pint. This pressure may then be expended continuously through the nasal applicator 7 to effect politzerization in the manner as previously described. This adaptation has the distinct advantage of providing the most inexpensive and universally available means for effecting politzerization. The sphygmomanometer shown in Fig. 3 is not provided with a safety pressure relief valve, although this feature may be supplied by the use of an aneroid manometer which are now commercially available and designed to relieve pressure above a predetermined maximum. However, whether the safety valve feature is employed in sphygmomanometers is not critically dangerous in view of the fact that sphygmomanometers are used only by experienced doctors or technicians who are accustomed to regulating pressure within the instrument through the medium of the pressure gauge 54.

The T section 4 is preferably capable of dismemberment so that it may likewise be employed as a straight section. This construction is particularly desirable so that a sphygmomanometer may be employed for its original purpose and likewise adapted as a politzerizer. As shown in Fig. 4, the section 4 may comprise a basic T member 60 having a tapered female element 61 in one cross-arm 62, and a tapered male element 63 on the other cross-arm 64. The branch arm 65 of the member 60 may be formed as a plug with its outer surfaces 66 corrugated so as to be inserted and retained within the end of the tube 5. A passageway 67 extends through the cross-arms 62 and 64 and forms a junction with a passage 68 which extends through branch-arm 65 and is in communication with the interior of tube 5.

Two plugs are arranged to be inserted within the severed ends of the tube 56, and these plugs are adapted to cooperate either with themselves or with the T member 60. One plug 70 having a passage 71 therethrough, is provided with a corrugated portion 72 to be seated within one of the severed ends of the tube 56. The plug 70 also has a tapered male element 73 adapted to cooperate with a corresponding female element. The other plug 75, having a passage 76, likewise has a corrugated portion 77 which is adapted to be seated in the other of the severed ends of the tube 56. The plug 75 is provided with a tapered female element 78. In view of the foregoing description, it will be seen that the male member 73 of the plug 70 may be inserted within the female member 78 of the plug 75, whereupon the tube 56 is unified and the sphygmomanometer may be employed as such. On the other hand, the male element 73 of the plug 70 may be seated within the female element 61 of the T member 60, and the female element 78 of the plug 75 may be seated over the male element 63 of the T member 60, whereupon the T section 4 is assembled and the apparatus is adapted as a politzerizer.

The present invention has advantages over all other continuous pressure politzerizers now in use. In the continuous pressure politzerizer using the oxygen equipment in an airplane or low pressure chamber as a source of pressure supply, two great dangers are evident. The greatest danger is the possibility of using excessive pressure caused

by mechanical failure of the reducing valve or improper bleeding of the pressure which might result in permanent damage to the tissues of the middle ear or ear drum. The other great disadvantage is the inflation of the middle ear cavity with pure oxygen. Within a few hours following descent from high altitudes of a person whose middle ear cavity has been inflated with pure oxygen, the oxygen will be absorbed through the tissues of the middle ear cavity leaving the patient in the same condition as before politzerization. If this oxygen is absorbed from the middle ear cavity during sleep, the reduced pressure may cause a serum exudate and even hemorrhage into the cavity producing a condition known as otitis media acute, with varying degrees of severity. In the present politzerization method and apparatus the above conditions are impossible because the middle ear cavity is always ventilated with normal atmospheric air and the pressure is so regulated that there is no danger of tissue damage, over inflation, or patient discomfort.

Another type of continuous pressure politzerizer in use at the present time is the one installed in low pressure chambers and utilizing the pressure differential between the simulated altitude inside the chamber and the ground level pressure surrounding the chamber for its operation. The great disadvantage of this instrument is the extreme variation in the pressure differential. At high altitudes, if the continuous pressure is applied for even a short period of time, a sufficient accumulated pressure may be built up in the patient's oral-nasal cavity to be harmful to the tissues of the middle ear cavity and ear drum if politzerization is accomplished. Patients being politzerized for the first time with this instrument are often difficult to treat because of the psychological effect of the hissing noise this instrument makes. Frequently, a number of attempts have to be made in order to accomplish successful politzerization. At low altitudes the pressure differential is so reduced that the instrument is not efficient. The wide range of pressures, running from 0 to approximately 500 mm. mercury pressure encountered in moving between sea level and 30,000 feet altitude, requires considerable variation in the technique of the application of this instrument and therefore, much experience on the part of the operator. In the politzerizer of this invention the pressure source is always constant so that no variation of technique need be employed, regardless of altitude. This simplicity of operation makes its use by inexperienced persons safe and easy. Also, the instrument is quiet and has nothing in its appearance to cause apprehension on the part of the patient. Therefore, there is no patient psychology factor to overcome.

During descent from high altitudes a patient may accomplish politzerization himself through employment of the Valsalva maneuver, which consists in the patient holding his nose and synchronizing a downward movement of his shoulders and a forward movement of his head with a forceable exhalation allowing his cheeks to puff and throat to relax, while breathing oxygen. By the use of this maneuver there is danger that the patient may inflate his middle ear cavity with a sufficient concentration of oxygen to cause a delayed aero otitis media acute through the absorption of this oxygen. If a pressure differential instrument is all that is available to treat the patient, he must be taken to a simulated altitude great enough to produce a pressure dif-

ferential sufficient for politzerization. This procedure is impractical and the equipment necessary therefor is not readily available.

As hereinbefore noted, the present method and apparatus have several distinct advantages over the prior art. The safety feature is evident in the fact that it is impossible to use pressures which would be harmful to a patient. This means that should emergency require the use of this instrument by an unskilled person, safe, efficient relief could be easily effected. The construction and operation of this instrument are such that its original cost would make it available to all persons having use for the instrument. There is no operating expense. The simplicity and the operation of the instrument make its use such that any operator may safely use it after a minimum of instruction and/or experience. The portability of this instrument lends itself to the use by general practitioners who may be required to perform politzerization in places other than their offices and operating rooms. The foregoing features of this instrument clearly demonstrate the ease of its operation which is one of its greatest advantages.

Although certain specific embodiments of the invention are shown and described, it is quite obvious that many modifications thereof are possible. The invention, therefore, is not to be restricted except insofar as is necessitated by the prior art and by the spirit of the appended claims.

That which is claimed, as new, is:

1. A portable politzerizer apparatus for relieving total or partial evacuation of the middle ear and which comprises a manually activated device for producing pressure, a surge tank receiving the pressure developed by said device, a mercury manometer for indicating and relieving above a predetermined degree the pressure within said surge tank, and a nozzle in communication with said surge tank for continuously releasing pressure therefrom.

2. A politzerizer which comprises a surge tank of about 500 cc. capacity, a hand bulb for pumping air into said surge tank, a mercury manometer for indicating and controlling the air pressure within said surge tank to a predetermined maximum, and an orificial applicator in communication with said surge tank for continuously releasing air under pressure therefrom.

3. A politzerizer which comprises a surge tank of about 500 cc. capacity, a hand bulb for pumping air into said surge tank, a mercury manometer for indicating the air pressure within said surge tank and for releasing pressure above that which is physiologically tolerable (in the order of magnitude of 200 mm. Hg) therefrom, and an orificial applicator in communication with said surge tank for continuously releasing air under pressure therefrom.

4. A politzerizer which comprises a surge tank, a hand bulb for pumping air into said surge tank and in communication with said surge tank by means of a tube, a T section in said tube and having two of its arms connected, respectively, with said bulb and surge tank, an orificial applicator connected to the third of said arms of said T section to continuously release air under pressure from said tube, and a manometer in direct communication with said surge tank for indicating the air pressure therein.

5. A politzerizer which comprises a surge tank, a hand bulb for pumping air into said surge tank and in communication with said surge tank by means of a tube, and a T section in said tube,

an orificial applicator connected to one arm of said T section and in communication with said surge tank to release air under pressure therefrom, and a mercury manometer in communication with said surge tank for indicating and controlling the air pressure therein, and a trap in communication with said manometer to trap the mercury in the event that it is expelled from the manometer by a sudden burst of pressure.

10. A politzerizer which comprises a surge tank, and a hand bulb for pumping air into said surge tank and in communication with said surge tank by means of a tube, a T section in said tube and having two of its arms connected, respectively, with said bulb and surge tank, an orificial applicator connected to the third of said arms of said T section to release air under pressure from said tube, means including a manometer and safety pressure exhaust having direct communication with said surge tank for indicating the air pressure therein and for releasing air therefrom which is in excess of a predetermined maximum.

15. In a sphygmomanometer, including a pressure bag having a manometer in communication therewith and a hand bulb connected thereto by a tube, the improvement comprising the said tube connection being separable, and a T section having one arm connected to an applicator for an orifice in the human head and its other arms being removably connected to said separable ends, respectively, of said tube, whereby the sphygmomanometer may be employed as a portable politzerizer.

20. A tube fitting for use with a sphygmomanometer to adapt the latter as a politzerizer, said fitting comprising a T section having communicating passages extending through its arms, two of the arms carrying separable extensions having passages therethrough, means on said extensions and the other of said arms of said section for receiving and retaining tubing thereto, and interengageable means on said extensions for joining the latter together with their passages in communication, when said extensions are separated from said T section.

25. A politzerizer which comprises a surge tank, a hand bulb for pumping air into said surge tank and in communication with said surge tank by means of a tube, said tube being severed to receive a jointed T section, said T section including two plug members which are inserted in the severed ends of said tube, respectively, and a T member having a plug on its branch-arm, said plug members being adapted to be releasably joined to form a straight section or releasably joined with respective cross-arms of the T member to form a T section, an orificial applicator connected to the branch-arm plug of said T section and thereby in communication with said surge tank to release air under pressure therefrom, and a manometer in communication with said surge tank for indicating the air pressure therein.

30. An apparatus for relieving total or partial evacuation of the middle ear and which comprises a device for producing pressure, a surge tank for retaining pressure developed by said device, an orificial applicator in communication with said surge tank for releasing air under pressure therefrom, and a mercury manometer for indicating the pressure of the air released by said applicator and for relieving the pressure within said surge tank when it exceeds a predetermined maximum, said surge tank being located between said applicator and said mercury manometer whereby said tank will trap the mercury if it is withdrawn

from the manometer by a reverse pressure and thereby prevent the expulsion of the mercury through said applicator.

11. A portable politzerizer apparatus for relieving total or partial evacuation of the middle ear and which consists of a manually actuatable air pressure producing device, a surge tank receiving the air pressure developed by said device, an official applicator connected in the line between said air pressure producing device and said tank, and a pressure indicating device in communication with the surge tank for indicating the pressure within the surge tank, whereby continuous air pressure may be emitted through the applicator without pressure fluctuations of wide amplitude, when the pressure in the surge tank has built up to any predetermined working pressure.

12. A portable politzerizer apparatus for relieving total or partial evacuation of the middle ear and which consists of a manually actuatable air pressure producing device, a surge tank receiving the air pressure developed by said device, an official applicator connected in the line between said air pressure producing device and said tank,

and a pressure responsive means in communication with the surge tank, other than thru the line of said applicator, for indicating the pressure within the surge tank and releasing from the surge tank a pressure above a predetermined maximum, whereby continuous air pressure may be emitted through the applicator without pressure fluctuations of wide amplitude, when the pressure in the surge tank has built up to any predetermined working pressure.
